UNITED STATES PATENT OFFICE.

JAMES R. MEAD, OF LEWES, DELAWARE, ASSIGNOR OF ONE-HALF TO
WILLIAM E. VEASEY, OF LEWES, DELAWARE.

SIGNALING APPARATUS.

SPECIFICATION forming part of Letters Patent No. 708,487, dated September 2, 1902.

Application filed November 5, 1901. Serial No. 81,243. (No model.)

To all whom it may concern:

Be it known that I, JAMES R. MEAD, a citizen of the United States, residing at Lewes, in the county of Sussex and State of Delaware, have invented a new and useful Signaling Apparatus, of which the following is a specification.

Ordinarily marine and other signaling has been carried on through the medium of flags hoisted to an elevation by suitable flag-halyards. As each flag is connected at one end only to its halyard, the disposition of the flag is entirely dependent upon the direction of the wind, and therefore the flag may not fly in a position to be conveniently read by the party to whom the message is to be delivered. Moreover, the fluttering of the flag renders the same difficult to be read, and in the event of a calm the flag hangs downwardly against the supporting-mast, and thereby displays its color only. Thus the flag system of signaling is unreliable and in any event difficult to read.

In view of the disadvantages pointed out it is the object of the present invention to provide for displaying signals in such a position as to be effectively exposed to the party for whom the message is intended independent of the direction of the wind prevailing at the time the signal is made. It is furthermore designed to overcome fluttering of the signals and to conveniently adjust the same so as to effectively display them to any point of the compass with respect to the signal-support as a center.

It will of course be understood that it is not designed to employ a new or particularly adapted signal-code, as the device is adapted for displaying the usual signal-flags disposed one above the other in the ordinary manner, but in addition thereto to overcome the fluttering thereof.

Another object is to provide for the convenient raising and lowering of the signal flags or elements and also to facilitate the interchange of position thereof, so that the range of the code may not be limited in any manner whatsoever.

With these and other objects in view the present invention consists in the combination and arrangement of parts, as will be herein-

after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of a signaling apparatus embodying the present invention. Fig. 2 is a vertical longitudinal sectional view thereof. Fig. 3 is a cross-sectional view taken on the line 3-3 of Fig. 2.

Like characters of reference designate corresponding parts in all the figures of the drawings.

In carrying out the present invention there is provided a suitable base 1, which is set in the ground or supported upon an elevated platform, as may be desired, and upon this base there is rotatably mounted a mast or tower, preferably in the form of a substantially rectangular frame, comprising opposite upright side members 2 and the respective top and bottom sills or cross-bars 3 and 4. The bottom sill or cross-bar is pivotally mounted upon the center of the base by means of a suitable pivot connection 5, and the upper cross-bar is also pivotally mounted to a cross-head 6, located above the frame or tower and connected to the top by means of a suitable pivot-bolt 7, there being a washer 8 interposed between the cross-head and the cross-bar. The cross-head is held against movement by means of the guy-rods or cables 9, which extend from each end of the cross-head and are anchored in the ground in any suitable manner. By this means the frame or tower is mounted to rotate upon a vertical central axis, and its rotation may be conveniently effected by means of a suitable handle 10, inclined laterally and upwardly from the lower end of the frame. The rotatable frame 95 may be locked in any position in any suitable way, preferably by means of an interlocking connection between the frame and the base—as, for instance, by a locking pin or bolt 11, carried by the bottom cross-bar and adapted to adjustably engage a series of sockets or recesses 12, formed in the top face of the base

and concentric with the pivotal axis of the frame.

For raising and lowering the signals there is provided a pair of endless halyards 13, which travel over the opposite ends of a rotatable drum 14, mounted between the opposite sides of the frame or tower adjacent to the lower end thereof, there being suitable blocks or guides 15 provided at the top of the tower or frame and upon the inner side thereof for the reception of the upper portions of the halyards, the drum of course being provided with any suitable operating means—as, for instance, a crank-handle 16, which is conveniently accessible from the ground or other support upon which the tower or frame may be placed. Upon the halyards are mounted a plurality of signal-carrying devices, each of which comprises top and bottom members or cross-bars 17 and 18, respectively, the opposite ends of which are slotted or bifurcated, as at 19, so as to slidably embrace the respective guide-rods 20, which are carried by the opposite edges of the respective sides of the upright frame or tower and are offset therefrom sufficiently to permit of the vertical movement of the cross-bars, which latter are connected to the halyards, as indicated at 21. The inner faces of the cross-bars are provided with the respective corresponding open-ended longitudinal grooves 22 and 23, which are designed for the detachable reception of a signal-slide 24, preferably comprising an open rectangular frame, to one or both sides of which is applied a covering of canvas, bunting, or other suitable material 25, of different colors and designs, according to the signal-code, thereby to form one of the signals. However, I also contemplate applying the present signal-flags directly to the slide or frame, preferably by sewing the flags to the textile covering of the slides.

It will of course be understood that the signal-carrying devices are provided at opposite sides of the tower or frame, so that either side of the latter may be turned into position for displaying the signals, and by the provision of a plurality of such holders a plurality of signals may be displayed one above the other in the usual manner.

As I contemplate employing a plurality of holders, one above the other, I have made the signal-slides horizontally insertible and removable, so that one signal-holder may not interfere with the signal-slide of the other, as would be the case if the signal-slides were removable vertically.

It will here be noted that there is no fluttering of the signal, as the latter is held practically rigid by the frame or slide, and thereby the signal is effectually displayed, and no mistake can be made within a reasonable distance. Moreover, the pairs of cross-bars forming the signal-holders are arranged at equal intervals, and the signal-frames are all of one size, so that any frame may be fitted to any of the holders, whereby the signals

are readily interchangeable, and the range of the code is not limited in any manner whatsoever.

In displaying the signal it will of course be understood that the supporting frame or tower is rotatably adjusted upon its vertical axis, so as to bring the signals in such a position as will most effectively display the same to the party for whom the message is intended, and in view of the practically rigid nature of the signal the latter is not affected by the prevailing wind, and neither does a calm have any effect upon the flags as now commonly displayed.

Although the present device has been particularly designed for marine signaling and to be set up on the shore for signaling vessels at sea, it may also be effectively employed upon vessels and, in fact, it may be used in any locality for signaling purposes of any character.

In view of the fact that the signal-holders are located at opposite sides of the mast or tower it will be understood that while the signals are being displayed upon one side of the device other signals may be set upon the other side of the device, so that after the first message has been delivered the second signal may be immediately displayed by merely reversing the mast or tower.

What I claim is—

1. In a signaling apparatus, the combination with a support which is rotatable upon its vertical axis, of vertically-movable signal-holders carried by opposite sides of the support, a plurality of signals for interchangeable engagement with the holders, and means for elevating and maintaining the signal-holder at one side of the support in an elevated and displayed position while the signal-holder at the opposite side of the support is held in a depressed position for receiving a signal.

2. In a signaling apparatus, the combination with a support which is rotatable upon its vertical axis, of vertically-slidable signal-holders carried by opposite sides of the support and movable from the bottom to the top thereof and vice versa, a plurality of signals for interchangeable engagement with the holders, and means for raising and lowering the signal-holders and to maintain the holder at one side of the support in an elevated and displayed position while the signal-holder at the opposite side of the support is in a depressed position for receiving a signal preparatory to being elevated.

3. In a signaling apparatus, the combination with a support which is rotatable upon its vertical axis, of vertically-movable signal-holders carried by opposite sides of the support and provided with guideways, a plurality of signal-slides for interchangeable engagement with the holders, and means for maintaining the signal-holder at one side of the support in an elevated and displayed position, while the signal-holder at the opposite

side of the support is in a depressed position for receiving a signal-slide.

4. In a signaling apparatus, the combination with an upright rotatable support, of 5 signal-holding means at opposite sides of the support, and means for simultaneously raising the signal-holding means at one side of the support and lowering the same upon the opposite side thereof, whereby signals may 10 be displayed in an elevated position at one side of the support while other signals are being set at the lower portion of the opposite side of the support, the support being rotatable to display the latter set of signals when 15 elevated.

5. In a signaling apparatus, the combination with an upright support which is rotatably adjustable upon a vertical axis, of an upstanding endless halyard carried by the support and working in opposite directions on opposite sides thereof, and signal-holders carried by the halyard and located at opposite sides of the support, whereby signals may be simultaneously elevated at one side of the 25 support and hauled down at the opposite side thereof, and signals may be set at one side while other signals may be displayed at the opposite side of the support.

6. In a signaling apparatus, the combination 30 of an upstanding rotatable support, means for adjustably rotating the same, a pair of upstanding endless halyards having corresponding portions at opposite sides of the support, and signals having their opposite ends connected to corresponding portions of the respective halyards, whereby signals may be set upon one side of the support while other signals are being displayed at the opposite side thereof.

40 7. In a signaling apparatus, the combination with an upstanding support, of a pair of upright rigid guides carried by the support, opposite upstanding halyards carried by the support, a signal-holder having substantially 45 horizontal top and bottom cross-bars connected respectively to the opposite halyards with their opposite ends slidably mounted upon the respective guides and provided in their inner faces with corresponding open-ended grooves, and a signal-slide removably 50 fitted in the grooves.

8. A signaling apparatus, comprising a mast or tower, a rigid vertical guide carried by the tower, a vertically-adjustable signal-holder 55 slidably mounted upon the guide and provided with a substantially horizontal open-ended guideway, and a removable signal-slide carried by the guideway and removable horizontally outward through the open end thereof.

60 9. A signaling apparatus comprising a mast or tower, a vertical rigid guide carried thereby, a vertically-adjustable signal-holder having corresponding substantially horizontal open-ended grooves, and a signal-slide removably fitted in the grooves.

10. A signaling apparatus, comprising a

70 mast or tower, a pair of vertical rigid guides carried thereby, a signal-holder having top and bottom cross-bars having their opposite ends slidably mounted upon the guides, and also provided with substantially horizontal corresponding open-ended grooves, a signal-slide removably fitted in the grooves, and means for raising and lowering the holder. 75

11. A signaling apparatus, comprising a mast or tower, opposite upstanding guide-rods carried thereby, a signal-holder slidably mounted upon the guide-rods and provided with a guideway, a signal-slide removably 80 carried by the guideway, and means for raising and lowering the holder.

12. A signaling apparatus, comprising a mast or tower, opposite upright guide-rods carried thereby, a signal-holder having substantially horizontal top and bottom cross-bars, which are provided with terminal openings receiving the guide-rods, and also having corresponding open-ended grooves in their 85 inner faces, a signal-slide removably fitted in the grooves, and means for raising and lowering the holder.

13. A signaling apparatus, comprising a mast or tower, opposite upright guide-rods carried by the tower, a drum carried by the 95 tower, guides mounted near the opposite end of the tower, endless halyards running over the guides and the drum, means for rotating the drum, signal-holders carried by the halyards, and slidably mounted upon the 100 guide-rods and removable signal-slides for the holder.

14. A signaling apparatus, comprising a mast or tower which is adjustably rotatable upon a vertical axis, a pair of halyards carried by and movable with the tower, and a signal connected at opposite ends to the halyards 105 to prevent fluttering of the signal.

15. In a signaling apparatus, a tower comprising a substantially rectangular frame 110 which is adjustably rotatable upon a vertical axis, opposite upright guides carried by the frame, a signal-holder having its opposite ends slidably mounted upon the guides, and a pair of halyards for raising and lowering the signal-holder, said halyards being connected to 115 opposite ends of the signal.

16. In a signaling apparatus, a tower comprising a substantially rectangular frame 120 which is rotatably adjustable upon a vertical axis, upright guide-rods carried by the opposite sides of the frame, a signal-holder slidably mounted at opposite ends upon the guides, a drum mounted within the lower part of the frame, means for rotating the drum, a 125 pair of pulley-blocks mounted upon the upper portion of the frame, and endless halyards reeved through the pulley-blocks and around the drum, the signal-holder being connected to the halyards. 130

17. In a signaling apparatus, a tower comprising a substantially rectangular frame which is adjustably rotatable upon a vertical axis, upright guide-rods carried by and offset

from the opposite sides of the upright side members of the frame, signal-holders located at opposite sides of the frame and slidably connected to the respective guide-rods, and 5 means for raising and lowering the signal-holders.

18. In a signaling apparatus, a tower comprising a substantially rectangular frame which is adjustably rotatable on a vertical 10 axis, a drum mounted within one end portion of the frame, means for operating the drum, guide-pulleys at the opposite end of the frame, halyards reeved through the guide-pulleys and around the drum, and signal-holders carried by the halyards and located at opposite 15 sides of the frame.

19. A signaling apparatus, comprising a base, a rotatable mast or tower mounted thereon, means carried by and adjustable upon the 20 tower into and out of engagement with the base to form an adjustable interlocking engagement between the mast or tower and the base, and a signal-holder carried by the mast or tower.

25 20. A signaling apparatus, comprising a base having a circular series of sockets in its upper face, a rotatable mast or tower mounted upon the base and concentrically with respect to the circular series of sockets, a locking-bolt carried by the mast or tower and in 30 operative relation to the series of sockets,

and a signal-holder carried by the mast or tower.

21. In a signaling apparatus, the combination with a base, of an upright substantially 35 rectangular frame mounted to rotate upon the base on a central vertical axis, an adjustable interlocking connection between the frame and the base, a drum mounted within the lower end of the frame, means for operating the drum, guide-pulleys mounted within the upper end of the frame, halyards reeved through the guide-pulleys and over the drum, guide-rods carried by the opposite edges of both side pieces of the frame, pairs 40 of signal-holding cross-bars having terminal perforations receiving the respective guide-rods, and also provided in their inner faces with corresponding open-ended grooves, signal-slides removably fitted in the grooves of 45 the cross-bars, each cross-bar being connected to the halyards, a cross-head swiveled to the upper end of the frame, and guys connected to the opposite ends of the cross-head.

In testimony that I claim the foregoing as 50 my own I have hereto affixed my signature in the presence of two witnesses.

JAMES R. MEAD.
